US00D872103S

(12) **United States Design Patent** (10) **Patent No.:** **US D872,103 S**
Doyle et al. (45) **Date of Patent:** **** Jan. 7, 2020**

(54) **DISPLAY SCREEN OR PORTION THEREOF WITH GRAPHICAL USER INTERFACE**

(71) Applicant: **Palantir Technologies, Inc.**, Palo Alto, CA (US)

(72) Inventors: **John Doyle**, District of Columbia, DC (US); **Jiawei Marvin Sum**, New York, NY (US); **Arseny Bogomolov**, Arlington, VA (US); **Eric Anderson**, District of Columbia, DC (US); **Eric Raboin**, McLean, VA (US); **Glenna Yu**, New York, NY (US); **Lucas Ray**, San Francisco, CA (US)

(73) Assignee: **PALANTIR TECHNOLOGIES, INC.**, Palo Alto, CA (US)

(**) Term: **15 Years**

(21) Appl. No.: **29/635,349**

(22) Filed: **Jan. 30, 2018**

Related U.S. Application Data

(63) Continuation of application No. 29/588,752, filed on Dec. 22, 2016, now Pat. No. Des. 810,101.

CLAIM

The ornamental design for a display screen or portion thereof with graphical user interface, as shown and described.

DESCRIPTION

The FIGURE is a front view of a display screen or portion thereof with graphical user interface showing our new design.

The outer perimeter shown in dashed broken lines in the FIGURE illustrates a display screen or portion thereof and forms no part of the claimed design. The remaining dashed broken lines in the FIGURE illustrate portions of the graphical user interface that form no part of the claimed design.
